UNITED STATES PATENT OFFICE.

JASPER H. SINGER, OF NEW YORK, N. Y.

BAGATELLE-BOARD.

SPECIFICATION forming part of Letters Patent No. 424,141, dated March 25, 1890.

Application filed October 12, 1889. Serial No. 326,819. (No model.)

To all whom it may concern:

Be it known that I, JASPER H. SINGER, of New York city, in the county and State of New York, have invented a new and Improved 5 Bagatelle-Board, of which the following is a full, clear, and exact description.

This invention relates to games, the object of the invention being to improve the game of bagatelle, and consequently to increase the 10 interest therein, the invention consisting, essentially, of a board, a revoluble pointer arranged in connection therewith, and a means for shooting a ball about the board, all as will be hereinafter more fully described, and specifically pointed out in the claim.

Reference is to be had to the accompanying drawings, forming a part of this specification, in which similar letters of reference indicate corresponding parts in both views.

20 Figure 1 is a plan view of a game-board embodying my invention; and Fig. 2 is a central longitudinal sectional view of the board, taken on the line xx in Fig. 1.

In the drawings, A represents a board, which 25 is arranged to be supported at one end by a block B, or any other convenient support. At the lower end of this board A there are a number of pockets C, each designated by a numeral, as shown. Upon the right of the board there 30 is an alley D, which constitutes a guideway for the marble or ball L used in playing the game. This marble or ball may be advanced through the alley in any desired way; but in practice I prefer to provide a plunger E, in connection with which I arrange a spring F, the arrangement being such that by drawing 35 the plunger in the direction of the arrow and against the tension of the spring, placing the marble in advance of the plunger, and in then 40 suddenly releasing the hold upon the plunger the marble will be advanced and travel up through the alley round the upper part of the board, and then down to the pockets C.

Upon the board there are arranged a number 45 of baffle-pins $a a$, and there are arranged other pins b , which constitute pockets or stops, each properly numbered. Near the lower end of the board, directly above the pockets C, I mark spaces c , to indicate the position 50 for markers H, against which the ball will strike in rolling down the board during the progress of the game, and the markers H, when so struck by the ball, will be thereby pushed or moved down into the numbered

spaces M, which are arranged below the 55 markers, and such movement of the markers will count according to the numbers given to the spaces M.

At any suitable place on the board I arrange a pivoted or revoluble arrow or pointer 60 K, and beneath or near the pointer I place suitable numbers—as, for example, 5, 10, 15, 20—and the number toward which the pointer points when it comes to rest will count when the game is played. If desired, the face of 65 the board beneath the pointer K may be provided with a dial I, divided into numbered spaces, as shown. Above the pointer K, I arrange a series of numbered spaces R, and upon the spaces I place movable pins R'. 70

In playing the game any desired set of rules can be adopted; but it will be found that by providing the board with a revolving pointer K the interest of the game will be materially increased, the object being to cause 75 the ball or marble L, that is advanced by the plunger or otherwise, to strike the pointer K, and cause it to revolve, so that it will point to the number or space designated by the highest numeral. 80

Although I have illustrated and described a board provided with but a single pointer, I desire it to be understood that two or more pointers might be employed, mounted in connection with one or more numbered dials or 85 spaces, and although I have mentioned a dial with numbered spaces, yet the spaces may have letters in place of numbers or characters, pictures, or simple colors, to which any desired values may be assigned when the 90 game is played.

Having thus fully described my invention, I claim as new and desire to secure by Letters Patent—

A bagatelle-board constructed for operation as herein shown and described, the same consisting of an inclined board A, provided with foot-pockets C, side alley D, and revolving pointer K, which latter is arranged between the mouth of the alley and the foot-pockets, whereby the alley-ball during its gravitation down the face of the board toward the foot-pockets may collide with the pointer, as and for the purpose set forth. 95

JASPER H. SINGER.
